UNITED STATES PATENT OFFICE

JOHN M. RAUHA, JR., AND ALEX MATTSON, OF OWEN, WISCONSIN

ROTARY VALVE

Application filed December 24, 1927. Serial No. 242,448.

This invention relates to rotary valves for internal combustion engines and its general object is to provide a rotary valve that is oil and air cooled, with the result it will be retained in a substantially cool condition at all times, therefore efficient operation thereof in that respect will be assured.

A further object of the invention is to provide a rotary valve for an internal combustion engine, that includes a sectional casing with a sectional bearing forming the lining of said casing, whereby access may be had to the valve in an easy and expeditious manner.

A still further object of the invention is to provide a rotary valve having enlarged portions formed therewith, with the valve ports formed in the enlarged portions, and the casing as well as the valve bearing being formed with compartments to accommodate the enlarged portions with the result casual displacement of the ports with respect to the cylinder, intake and exhaust manifold passages will be eliminated. Therefore accurate registration of the ports and passages will be assured.

Another object of the invention is to provide a rotary valve for internal combustion engines that has an oiling system for supplying the same with sufficient oil at all times.

A still further object of the invention is to provide a rotary valve structure of the character set forth that is extremely simple in construction, inexpensive to manufacture and efficient in operation and service.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:

Figure 1 is an end elevation of an internal combustion engine showing the application of our valve construction thereto and the means for operating the valve.

Figure 2 is a sectional view taken through

the engine and valve structure with the valve arranged in intake position.

Figure 3 is a similar view with the valve arranged in position for firing.

Figure 4 is a similar view with the valve arranged in exhaust position.

Figure 5 is a sectional view showing the sectional valve bearing and the oiling means.

Figure 6 is a view of the valve per se constructed for a four cylinder engine.

Figure 7 is a fragmentary view illustrating the arrangement of the cooling grooves.

Referring to the drawings in detail, the letter A indicates the block of the engine as shown, and B the head thereof. While the engine as suggested from the construction of the valve per se as shown in Figure 6, is shown as being a four cylinder four cycle type, we want it understood that the valve can be used for any type of engine without departing from the spirit of the invention. The head is formed with substantially concaved combustion chambers C which have the sides adjacent to the valve inclined toward the same, and these inclined walls merge into passages D that are disposed in communication with the valve casing as clearly shown in Figures 2, 3 and 4 of the drawings.

The valve casing is formed from sections, namely a lower section 1 which is formed with the block and an upper section 2 which is formed with the head and the casing is disposed laterally of the block as shown.

The casing is formed with a plurality of spaced parallel grooves formed in its outer surface so that the valve will be substantially air cooled as will be apparent, the grooves forming a substantially fin like construction for that purpose and are indicated by the reference numerals 2'.

The upper and lower sections are provided with cooperating flanges 3 that are formed with openings to accommodate bolt and nut connections 4 for securing the sections together when the head is fixed to the block through the medium of the bolts as shown, and the upper section is formed with exhaust passages 5 while the lower section is formed with intake passages 6. These passages are provided with manifolds, an exhaust mani-

fold 7 for the exhaust passages and an intake manifold 8 for the intake passages.

The valve 9 which as best shown in Figure 6 is of course cylindrical in formation and has formed thereon enlargements 10 that are provided with arcuate shape passages 11. While we have shown four enlargements 10 in Figure 6, it will be obvious that this number is employed for a four cylinder engine, and the 10 number of enlargements depends upon the number of cylinders.

The casing is provided with chambers to accommodate the enlargements 10 and a sectional bearing for the valve is arranged in the 15 casing in a manner to provide a lining for the latter and the bearing of course is enlarged at spaced intervals so that the enlarged portions of the bearing will fit within the chambers of the casing. The bearing is 20 likewise formed into sections, and includes an upper section 12 and a lower section 13. The sections 12 and 13 have their confronting edges reduced to provide tongues 14 disposed in overlapped relation as clearly shown 25 in Figures 2, 3 and 4. The bearing is provided with openings throughout its length so as to communicate with the respective passages, namely the cylinder passages, the exhaust passages and the intake passages. By 30 forming the casing and bearing into sections as above set forth, it will be apparent that ready access may be had to the valve by merely removing the head B.

The flanges 3 are provided with cut-out 35 arcs 3' forming a part of the grooves 2' as best shown in Figure 2, and the grooves extend inwardly to the bearing and have their ends terminating adjacent the exhaust and intake passages so that the bearing will be 40 cooled to retain the valve 9 in a cooled condition as will be apparent.

Arranged at intervals in the upper section 2 of the valve casing is a plurality of openings which are disposed in registration with 45 like openings formed in the upper section of the bearing, and disposed in these openings are nipples 15 that are threadedly secured at their inner ends in the upper section of the bearing as shown in Figure 5 and the outer 50 ends of the nipples 15 are provided with reduced threaded portions to accommodate coupling sleeves 16, which are threadedly secured to adjacent ends of pipe sections 17 for securing the latter into communication with the nipples.

The pipe sections 17 extend in arcuate formation from the nipples, and are thence bent at right angles as at 18 upon themselves to provide straight portions 19. At the 60 juncture of the curved portions with the straight portions, the pipe sections are provided with flat arms 20 that have openings formed in the outer ends thereof to be received by the bolts of the bolt and nut connections 4, with the result the pipe sections will

be held in secure position. A manifold, not shown, is secured to the lower ends of the straight portions 19 and this manifold may be in communication with the crank case of the engine, whereby the oil pumping system 70 will supply efficient amount of oil to the bearing, the oil cooperating with the air to retain the valve in a cool condition which will of course assure proper operation of the valve in this respect.

The valve is provided at one of its ends with a trunnion or stub shaft 21 which has secured thereto in any appropriate manner a gear 22, while secured to the block in opposed relation with respect to the valve is a 80 stub shaft which receives a gear 23, and fixed to a shaft 24 is a relatively large gear 25 and a relatively small gear 26. However, the small gear 26 is of the same size as the gears 22 and 23, and a similar size gear which is 85 indicated by the reference numeral 27 is secured to the crank shaft of the engine.

The gear 27 meshes with the large gear 25 whereby the shaft 24 is rotated for imparting rotation to the gear 26 which has trained 90 thereabout a sprocket chain 28 that is also trained about the gears 22 and 23 as shown in Figure 1.

From the above description and disclosure of the drawings, it will be obvious that we 95 have provided a rotary valve construction that is extremely simple and due to the grooving of the valve casing and the manner of supplying oil to the valve, the valve will be 100 retained in a cool condition at all times. The enlargements formed on the valve per se as shown in Figure 6 and which are disposed in the compartments therefor, positively eliminate end thrust of the valve, with the result the passages that are formed in the enlargements will accurately register with the cylinder, intake and exhaust passages.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:

1. The combination with an internal combustion engine having a removable head, a valve casing including an upper section formed with the head, a lower section formed with the block of the engine, said valve casing being grooved to provide air spaces extending therethrough, a cylinder valve arranged in said casing, enlargements formed with said cylindrical valve and being provided with arcuate shape passages adapted to communicate with passages to the cylinders of the engine and passages to the exhaust and intake manifolds of the engine, and means for oiling the valve, flanges formed with the sec- 120
- 125
- 130

tions of the valve casing and having bores registering with the grooves, and said grooves, bores and oiling means being adapted to retain the valve in a cool condition.

5 2. In an engine, a sectional casing formed with compartments, a valve mounted for rotation in said casing, a sectional bearing lining in said casing and extending into the compartments, overlapping tongues formed with
10 said bearings, nipples secured in openings formed in the casing and sectional bearing respectively, threaded reduced outer ends formed with said nipples, pipe sections for conveying oil to the nipples and being secured thereto, and flat arms formed with said pipe sections and being secured to the casing.

15 3. In a rotary valve, a casing, a bearing forming a lining for said casing, a valve mounted for rotation in said casing, nipples threadedly secured in openings formed in the bearing and extending through the casing, reduced threaded outer ends formed with said nipples, pipe sections including arcuate shape portions having threaded ends, couplings securing the threaded ends of the pipe sections to the reduced threaded ends of the nipples, straight portions included in said pipe sections and being in communication with a source of oil supply, flat arms formed with
20 the pipe sections at the juncture of the arcuate portions with the straight portions, and means for securing said arms to the casing.

Owen, Wis., July 8, 1927.

JOHN M. RAUHA, JR.
ALEX MATTSON.
